ILLUMINATED GLOBE

Raymond R. Dupler, Toledo, Ohio

Application February 24, 1940, Serial No. 320,559

1 Claim. (Cl. 240—2)

This invention relates to illuminated globes such, for example, as terrestrial and celestial globes, which are mounted on a standard or other suitable support and are lighted in such manner that the exterior surface of the globe is illuminated, thus facilitating the examination thereof, and an object is to produce a new and improved illuminated globe of the above character in which the lamp is disposed outside of the globe and the arrangement being such that the globe is satisfactorily and efficiently illuminated and the cost of the assembly being materially reduced.

For purposes of illustration but not of limitation, an embodiment of the invention is shown on the accompanying drawing in which the figure is a side elevation, partly in section, of an illuminated globe and supporting standard therefor.

The illustrated embodiment of the invention comprises a standard having a base 10 carrying an upstanding yoke having arms 11 and 12. Formed in the standard is a vertically disposed opening 13, the upper portion of which flares outwardly, the opening or socket 13 being open ended. Disposed within the opening 13 is a bracket 14 to receive an electric light bulb 15, the wires 16 for the bracket 14 leading through the bottom end of the opening 13 and having a plug 17 of the usual character at the opposite end thereof. For directing the light rays upwardly is a reflector 18 arranged within the opening 13. In the outer end of the opening 13 is a lens 19 which is suitably held in place by a ring 20.

Carried by the outer ends of the yoke arms 11 and 12 by rivet pins 21 is a meridian ring 22 and carried by the meridian ring 22 is a globe 23, the walls of which are of glass or other suitable translucent material. The globe 23 is mounted for rotative movements within the ring 22 by diametrically opposed supports 24 and 25, one of which is preferably releasable to enable the globe to be assembled as will be readily understood by those skilled in this art. The globe 23 is covered by a series of gores 26 which may contain any suitable pictorial illustration such, for example, as a terrestrial or celestial map. The gores 26 are preferably of relatively thin sheet material of

translucent character as, for example, relatively thin parchment paper.

It will be manifest that the arrangement is such that the form of lens 19 is not critical, except that it shall confine the directed rays to the globe surface, thereby to obviate stray rays beyond such surface which would cause glare interfering with reading of the indicia, and in order fully and satisfactorily to illuminate the globe. The light rays 5 penetrate through the translucent gores 26 and through the walls of the globe 23 in order to illuminate the outer surface of the globe, thereby to facilitate the examination of the indicia on the gores. In this manner an exceedingly inexpensive 10 illuminated globe may be produced, eliminating the costly features normally attendant to an illuminated globe in which the lamp is positioned inside of the globe. It will be recognized that the intensity of the light rays must be sufficient to 15 penetrate through the gores as well as the walls of the globe in order to light up all portions of the globe. An important advantage of the above described arrangement resides in the fact that substantially the entire surface of the globe is 20 illuminated and in such manner that examination thereof can be readily made. This is a decided improvement over illuminated globes which obtain their illumination from a lamp disposed inside of the globe because in such structures, a dark spot 25 exists where the lamp enters the globe.

It is to be understood that numerous changes in details of construction, arrangement and operation may be effected without departing from the spirit of the invention especially as defined in the 30 appended claim.

What I claim is:

The combination of an indicia-carrying globe of 35 translucent material, a support for pivotally mounting said globe in spaced relation thereto, said globe support formed with a recess, a light source mounted in such recess to be shielded thereby from an observer, and a lens mounted in the open end of such recess for confining the directed light rays to the maximum area of the globe surface which is presented to said light source.

RAYMOND R. DUPLER.
